DESIGN FOR A MEDALLION OR THE LIKE

Irma Neu, New York, N. Y.

Application December 9, 1937, Serial No. 73,501

Term of patent 3½ years

To all whom it may concern:

Be it known that I, Irma Neu, a citizen of the United States of America, residing in New York city, in the Borough of Manhattan, county and State of New York, have invented a new, original, and ornamental Design for a Medallion or the like, of which the following is a specification, reference being had to the accompanying drawing, forming part thereof, wherein,

The characteristic feature of my design resides in the combination of the frame and painted faille fabric shown.

I claim:

The ornamental design for a medallion or the like, substantially as shown and described.

IRMA NEU.
